FURNACE BOTTOM

Thomas E. Murray, Jr., Brooklyn, N. Y.

Application January 19, 1935, Serial No. 2,606

4 Claims. (Cl. 122—235)

The invention aims to provide a floor for furnaces of boilers or the like which is economical and durable and has other advantages referred to in detail hereinafter.

5 Fig. 1 is a longitudinal section of a boiler. Fig. 2 is a plan of a part of the floor. Fig. 3 is a side elevation of one of the tubes. Referring to Fig. 1, the boiler 11 may comprise any usual or suitable arrangement of water tubes located above a furnace combustion chamber 12. Pulverized fuel burners 13 project the flame downward whence it turns upward, filling the chamber and passing through the overhead tubes. The front wall comprises vertical tubes 14 with flanges 15 between them and spaces through which air is admitted for combustion. The rear wall comprises similar tubes 15 with an outer covering of insulating material. The floor of the chamber comprises a number of tubes 16 inclined downwardly toward the front and connected by headers 17 and 18 to the tubes of the front and back walls and thus into the circulation of the boiler. The water circulating through the floor tubes is heated and at the same time keeps the floor comparatively cool. Ashes and slag deposited thereon are cooled and are sufficiently granular to pass through the spaces between the tubes.

The tubes are spaced apart as in Fig. 2 and have projections 19 extending outward therefrom, the projections from two adjacent tubes extending approximately across the space between them. The projections on the tubes provide an extension of the area exposed to the hot ashes and slag and increase the rapidity of the heat exchange with the water within.

35 Preferably the projections are comparatively small at their ends and are welded at such ends with resistance butt welds to the tubes. A plurality of such projections closely spaced is advantageous. It has been found that where flanges or projections are united by comparatively long welds, say more than twelve inches, the welding operation sets up strains in the tubes upon contraction which may cause them to fail in use and 40 also sets up strains in the projections which decreases their resistance to oxidation, particularly at high temperatures, and thus reduces the width to which they may be extended beyond the tubes without burning out in practice.

50 The spaces between the projections 19 are sufficient to pass ashes to the pit below. The space from one projection 19 to the next is at least equal to the dimension of the projection lengthwise of the tube, and may be greater as illus-

trated. This relation is obtained and maximum surface exposure secured, by making the projections of greater dimensions transversely than lengthwise of the tube.

The front wall illustrated is the invention of 5 John H. Lawrence and is claimed in his co-pending application Serial No. 4,051, filed January 30, 1935.

Various other modifications may be made by those skilled in the art without departing from 10 the invention as defined in the following claims.

What I claim is:

1. A furnace for boilers or the like for burning fuel in suspension having a bottom comprising parallel tubes spaced apart, each having in heat-conducting engagement with it a series of spaced short metal projections extending toward the next tube, the projections being in the form of thin plates with their narrow edges approximately horizontal and their wider faces approximately 15 vertical.

2. A furnace for boilers or the like for burning fuel in suspension having a bottom comprising parallel tubes spaced apart, each having in heat-conducting engagement with it a series of spaced short metal projections extending toward the next tube, the projections having their vertical 25 dimension greater than their dimension lengthwise of the tubes.

3. A furnace for boilers or the like for burning fuel in suspension having a bottom comprising parallel tubes spaced apart, each having in heat-conducting engagement with it a series of spaced short metal projections extending toward the next tube, the spaces being sufficient to pass substantially all the ashes to the floor below and the 30 dimensions of the projections lengthwise of the tubes being less than said spaces and being so slight as to offer no substantial support for an accumulation of ashes.

4. A furnace for boilers or the like for burning fuel in suspension having a bottom screen comprising substantially parallel tubes spaced apart, at least some of said tubes having in heat-conducting engagement with them a series of spaced short metal projections extending toward the next tube, the spaces being sufficient to pass substantially all the ashes to the floor below and the dimensions of the projections lengthwise of the tubes being less than said spaces and being 45 so slight as to offer no substantial support for an accumulation of ashes.
